UNITED STATES PATENT OFFICE.

JULIUS HEUSSER, OF CLEAR LAKE, WISCONSIN.

VENTILATED CAN COVER.

Application filed April 23, 1925. Serial No. 25,407.

To all whom it may concern:

Be it known that I, JULIUS HEUSSER, a citizen of the United States, residing at Clear Lake, in the county of Polk and State 5 of Wisconsin, have invented certain new and useful Improvements in Ventilated Can Covers; and I do declare the following to be a full, clear, and exact description of the invention, such as will enable others skilled in 10 the art to which it appertains to make and use the same.

My invention relates to improvements in ventilated covers for milk and cream cans, and it is the object of such invention to provide 15 a single ventilated cover having an external, continuous seat, which will fit tightly upon the necks of cans, whether said necks be rather widely flared, or flared to a less extent. These flared neck ends are commonly 20 provided with openings which are instrumental in securing the can tops to the cans for shipment, and unless a ventilated cover, used upon a can of this character, tightly fits the flared end of the neck, there is danger 25 of flies or other insects entering the can through the openings in question. It is therefore of extreme importance to provide for tight engagement between the ventilated cover and the flared neck, regardless of the 30 degree to which the latter is flared. Ordinarily, in milk and cream cans as now manufactured, the angle of the flare is either 33° or 37°, and it is my intent at the present 35 time, to provide a closure which will tightly engage the neck of either style can, it being understood however, that the invention is not restricted to any two angles on the external flare-engaging seat.

In the accompanying drawing, forming 40 part of this application, Figures 1 and 2 are vertical sectional views partly in elevation showing the application of the improved ventilated cover to can necks having different flares.

45 In the drawing above briefly described, C designates a ventilated cover whose general construction forms no part of the present invention but is protected by my pending U. S. application Serial No. 17,790, filed March 50 23, 1925. It is the unique seat only of the cover which I seek to protect by the present application. This seat is designated in a general way by the character S, it is dis-

posed at the lower exterior portion of the cover C, and is continuous. Moreover, the 55 seat has an upper continuous bevel 1 and a lower continuous bevel 2, these bevels 1 and 2 being disposed at two distinct angles with respect to the vertical or horizontal. Thus, one of the bevel seat portions will tightly 60 rest upon a can neck flared at one angle, while the other bevel seat portion will similarly engage a different sized neck having a flared end at a different angle. This will readily be seen by comparing Figs. 1 and 2. 65

In the preferred form of construction, when the cover is made to fit standard cans of the sizes and types now found upon the market, one of the bevel seat portions will be disposed at an angle of 33°, and the other 70 at an angle of 37°. These particular angles however are not shown in the drawing, as the difference between them would be so slight as to appear practically infinitesimal, on the small scale necessarily followed in 75 the drawing. Moreover, it is to be understood that the invention is not restricted to the use of any specific angles, it being sufficient that the two seat surfaces shall be at two distinct angles to meet demands. 80

By constructing the device in the manner disclosed, it may readily be used in connection with either style of can commonly found in dairy, arm, creamery, or the like. Otherwise, two sets of ventilated closures would 85 be necessary, having seats with different bevels to fit the different flares of can necks, which obviously would be highly impractical.

As excellent results are obtainable from 90 the details shown, they are preferably followed. However, within the scope of the invention as claimed, modifications may be made.

I claim: 95
A ventilated cover having a continuous external seat, said seat having upper and lower bevels at two distinct angles, one bevel being adapted to rest tightly on a widely flared milk or cream can neck, the other 100 bevel being adapted for similar engagement with a less widely flared neck.

In testimony whereof I have hereunto affixed my signature.

JULIUS HEUSSER.
